UNITED STATES PATENT OFFICE.

ABRAHAM N. WOLF, OF ALLENTOWN, PENNSYLVANIA.

ROLLER FLOUR-MILL.

SPECIFICATION forming part of Letters Patent No. 294,947, dated March 11, 1884.

Application filed August 20, 1883. (No model.)

To all whom it may concern:

Be it known that I, A. N. WOLF, of Allentown, in the county of Lehigh and State of Pennsylvania, have invented certain new and useful Improvements in Roller Flour-Mills; and I do hereby declare the following to be a full, clear, and exact description of the invention, such as will enable others skilled in the art to which it pertains to make and use the same, reference being had to the accompanying drawings, which form part of this specification.

Figure 1 is a side elevation of a mill embodying my invention. Fig. 2 is a front elevation of a roller-mill having a single pair of rolls, the frame-work being shown in section. Fig. 3 is a vertical section taken through the hopper. Fig. 4 is a perspective of the feed-board, part of its attachments, the cut-off, and the feed-roller. Figs. 5, 6, 7, and 8 are detail views of the cam and other parts used in connection with the lever D'.

A³ represents the hopper, in which is suspended at the points b², by means of the arms A⁴, the feeding-board A. The upper edge of the board A catches under the shield A⁵ for the purpose of preventing any passage of the grain past this edge of the board. This board A, through the pins or connections a², is connected to the levers a, placed upon the outside of both ends of the hopper, and which levers a are pivoted at their upper ends to the links connected with the bell-crank-levers A'. The arrangement and construction of these operating parts are the same upon each end of the hopper. The lower ends of these levers a bear against the two cams L upon the ends of the shaft of the feed-roller M, and as the shaft is made to revolve, these levers a are caused to vibrate, and this vibratory movement is in turn imparted to the board A, for the purpose of keeping up an even and regular feed through the connections a². These connections a² pass through suitable slots in the side of the hopper, and thus cause the levers A⁴ and a to always move together. By thus connecting the levers A⁴ and a rigidly together by means of the connections a², they have the same movement, and hence the movement imparted to the levers a by the cams L is imparted to the feed-board. The levers a are thrown off or on cams L by means of the bell-crank levers A',

which are connected at the upper ends of their short arms to the upper ends of the said levers a. By throwing the bell-crank levers A' upward, the levers a are thrown back at their upper ends, and being pivoted to the feed-board at the pins a², the lower ends of said levers a are thrown forward and away from the cams L, as shown by dotted lines in Fig. 1, and the vibrating or swinging of the feed-board is thus instantly stopped. By bringing the levers A' back to their central and horizontal positions, the swinging motion of the feed-board is resumed. The levers A' also control the size of the opening between the feed-board A and the curved surface of the cut-off N, through which opening the grain is fed to the rolls. As the levers A' are moved downward, the upper ends of the arms a are thrown forward, while their lower ends resting against the cams are fixed, and the feed-board A, being secured to the arms a at a², is carried forward with it and away from the cut-off N, as shown by dotted lines, thus increasing the opening between them and allowing a larger quantity of grain to pass. The feeding of the grain is further regulated automatically by the cut-off N and the plate N', the latter being balanced at the fulcrum A² by the counter-weight, shown inside of the hopper at the rear, and connected to the cut-off N by a link and lever, as shown. Feed-roller M revolves from right to left, and the grain passes to the grinding-rolls between it and the inner edge of the cut-off N. By bringing the edge of the cut-off N in contact with the feed-roller M, the feed is stopped, and the quantity fed to the rolls is regulated by the opening between them. The grain falling from the top of the hopper lights first upon the plate N', which swings with the feed-board A. Any accumulation of grain upon the plate N' bears it down and turns the cut-off N back and away from the feed-roller M by means of the link and lever connecting them. The space between M and N being thus increased, a greater quantity of grain passes through. As soon as the plate N' is relieved of the weight upon it, it is raised again to its place by means of the counter-weight d², shown in the rear, and by the same movement the cut-off N is again moved forward closer to the feed-roller M to diminish the feed or cut it off entirely, as the case may be.

The bearings of one roll, Y, are rigidly secured to the top plate of the frame O', while the bearings of the other roll, Y', are fixed in levers B, so constructed as to admit of adjustment of said roll toward or away from the roll in rigid bearings. By this construction I am able, by my invention, to adjust the parts quickly and with accuracy, so that between the two ends of the rolls there is not the slightest variation. The levers B at the two ends of the adjustable roll are precisely alike. They rest at the lower extremities of the inner arms upon the pins B', upon which they also turn in adjusting. The other and longer arms of these levers B extend outward, and are turned down so as to clear the outer edge of the framework O' and O. In the under sides, at the outer ends of the levers B, are the inverted V-shaped recesses, where they rest upon the knife-edges upon the upper sides of the ends of the spring-actuated bar C, which extends across the mill from side to side, and supports upon its ends the outer extremities of both the levers B, which carry the roll Y'. The spring-actuated bar C is kept up against the levers B by means of a strong spiral spring contained in the box F, cored out in the middle of the bar, and this bar is clamped against the outer ends of the levers B by means of the hand-wheel D, resting upon the top frame, O', and a bolt, C', passing through the coil-spring and the bar C, and having a thread cut upon its upper end. A thread is also cut upon the lower end of the bolt C', and a shoulder is turned upon the bolt, which rests upon the top of the bar C. By means of the nut on the lower end of the bolt C' and the shoulder resting on the bar C, the tension of the coil-spring contained in the box F is regulated, so that it may be stronger or weaker according to the work required. Thus by turning the hand-wheel D the bar C is lifted, and by it the outer end of both levers B raised, thus bringing the adjustable roll Y' nearer to the roll Y. It is moved away from Y by turning the hand-wheel D in the opposite direction. Upon the top of each lever B, near the outer end, is hand-wheel E, through which a bolt, E', passes downward through B, and is tapped into the top frame, O'. This is set at such a point as to prevent the roll Y' from coming into actual contact with the roll Y, however close may be the adjustment. The hand-lever D' is used to throw the rolls apart instantly and by a single movement. The bolt passing up through the spiral spring F passes also through the inner end of the lever D'. In the under side of the inner end of D' is cut a spiral, y, engaging with another, x, upon the upper side of a boss, 60 a⁵, resting upon the top of the top frame, O'. The spiral or incline x on the boss engages with a corresponding spiral or incline, y, in the end of the lever D', so that when the lever is turned in one direction it is forced upward, and when turned in the other it sinks downward. Thus by turning the lever D' the rolls Y and Y' may be instantly thrown apart, and by turning D'

in the opposite direction they may be instantly brought together again without altering or disturbing in the least the adjustment 7c made through the hand-wheel D. This is a great advantage in stopping and starting rolls. The rolls are separated for this purpose by means of the lever D' alone, and the rolls, after being once accurately set for their work, need 75 not be altered at all, no matter how often the mill may be stopped.

By means of the levers B, the bar C, and the spiral spring supporting them, any obstruction or foreign substance which may possibly 80 get between the rolls with the grain will be allowed to pass without disturbing the adjustment or injuring any of the parts. It will for an instant force the adjustable roll Y' away from the fixed roll Y, forcing the outer 85 arms of the levers B and the ends of the bar C downward. As soon as it has passed from the rolls the roll Y' will be brought back to its place by means of the coil-spring F. The revolving brush G is arranged in a spiral upon 90 the drum G'. The drum G', having the bristles G secured thereto so as to form a spiral brush, is journaled in the frame just under the rolls Y Y'. Just under this spiral brush G G' is formed a concave, f³, with which the 95 bristles G come in contact. As the brush G G' is made to revolve, the spirally-arranged bristles cause the ground grain to move from one end of the concave toward the discharge at the other end. The bristles strike the lower 100 sides of both rolls Y Y' as they revolve, and brush from them all matter that may adhere to them, keeping the rolls clean and bright at all times. The brush itself is kept properly 105 clean and free from gathering matter by the sweeping or striking action of the bristles as they revolve and come in contact with the faces of the rolls above. The revolving brush, by means of its centrifugal force and sweeping action against the rolls, is itself kept 110 clean, and at the same time removes every substance from the rolls. The revolving brush, being spiral in form, acts also as a conveyor, throwing lengthwise as well as cross- 115 wise, and conveying the broken wheat to one end of the concave, where it passes through the spout P into one end of the scalping-reel, where, by means of the lifting plates or blades H and the brushes I, acting against the wire-cloth J, the smaller parts of the broken grain 120 are separated from the coarser.

Having thus described my invention, I claim—

1. The combination of the hopper provided with slots through its ends, the swinging levers, which are pivoted at their upper ends inside thereof, and have the feed-board connected to them near their lower ends, and a mechanism which is connected with the pivoted levers for causing them to reciprocate, 125 and thus keep the feed-board in motion, substantially as shown and described.

2. The combination of the hopper, the swinging feed-board, pivoted arms connected there-

to, pivoted levers upon the outside of the hopper, and revolving cams for moving the levers, and thereby imparting a constant reciprocating motion to the board, substantially as shown 5 and described.

3. The combination of the hopper, the reciprocating feed-board, pivoted arms A^4 , connected thereto, the pivoted operating-levers upon the outer ends of the hopper, and operating-cams, with the bell-crank levers A' and connecting-links, substantially as set forth.

4. The combination of the frame, the bar C , provided with the box F , the spiraled boss a^5 x , the bolt which passes through the bar, the 15 coil-spring, and a hand-lever having a spiral formed at its inner end, substantially as specified.

5. The combination of the frame, the two side levers, B , the bolts and wheels $E E'$, connected therewith, the levers D' , the spiraled 20 boss a^5 x , bolt C , bar C' , and coil-spring, substantially as shown.

6. The combination of the rolls $Y Y'$, a revolving spiral brush, G , which brushes both rollers at once, the trough f^3 , the scalping-reel 25 I , and screen J , substantially as shown and described.

In testimony whereof I affix my signature in presence of two witnesses.
